UNITED STATES PATENT OFFICE.

GEORGE ALBERT LYON, OF PHILADELPHIA, PENNSYLVANIA.

BUFFER FOR AUTOMOBILES.

1,325,730.

Specification of Letters Patent. Patented Dec. 23, 1919.

Application filed October 5, 1917. Serial No. 194,855.

To all whom it may concern:

Be it known that I, GEORGE ALBERT LYON, a citizen of the United States, and resident of Philadelphia, county of Philadelphia, State of Pennsylvania, have made a certain new and useful Invention Relating to Buffers for Automobiles, of which the following is a specification, taken in connection with the accompanying drawing.

The invention of this application, which is a continuation in part of my co-pending applications, Serial No. 877,887, filed December 18, 1914 and Serial No. 170,129, filed May 22, 1917, that is, contains subject-matter taken from these prior cases, relates especially to automobile buffers formed of resilient strips of steel or other metal which are given an arched or bent cross-section to increase their stiffness or resistance to bending in a horizontal direction and also minimize relative vertical movement between engaging portions of such curved section strips. In this way some or all parts of the resilient strips may be stiffened and strengthened and in this way preferably leaving flat the sharpest bends or end portions where the bending stresses are greatest a considerable saving in the weight of strips may be effected. The upper and also the lower edges of the front or impact receiving portions of the spring strips may be backwardly relieved or beveled to render them relatively inconspicuous and may also be finished with a relatively inconspicuously colored protective coating as compared to the nickel plated front faces of the strips.

In the accompanying drawings which show in a somewhat diagrammatic way various illustrative embodiments of the invention,

Figure 1 is a plan view of a buffer and connected supporting device secured to a Ford automobile.

Fig. 2 is a side view taken substantially along the line 2—2 of Fig. 1.

Fig. 3 is a plan view showing another form of resilient buffer.

Fig. 4 is an enlarged detail section taken along the line 4—4 of Fig. 1.

Fig. 5 is a partial section taken along the line 5—5 of Fig. 3.

Fig. 6 is an enlarged detail section taken along the line 6—6 of Fig. 3.

Fig. 7 is a plan view of another form of resilient buffer member which is shown as composed of a single spring strip.

Fig. 8 shows another form of buffer formed of two connected spring strips.

Fig. 9 is a side sectional view taken along the line 9—9 of Fig. 8. 60

Fig. 10 is an enlarged sectional view taken along the line 10—10 of Fig. 8.

Fig. 11 is a plan view showing still another form of buffer; and

Fig. 12 is an enlarged section taken along the line 12—12 of Fig. 11. 65

The resilient buffer shown in Fig. 1 comprises two spring strips 1 and 2 extending transversely across the front of the automobile to form impact receiving members, the end portions of these strips overlapping and reinforcing one another and being adjustably held in desired position by any suitable clips, such as 17, of the general construction shown in the Lyon Patent 1,198,246 of September 12, 1916, and which may be tightened by screwing up the bolts 18. The ends 19, 20 of these impact receiving members are preferably arranged substantially in front of the automobile frame members 7 and the connected portions 3 may extend outward and backward from the doubled reinforced front portion of the buffer so as to extend into protective position in front of the vehicle wheels and form the open end loops 4 connected by the inwardly and rearwardly curving portions 5 to the attaching members or ends 6 of the strips. These attaching members may be connected to Ford automobiles by means of substantially rigid flanged extension supporting members which may comprise the angular forward portions 14 having as indicated in Figs. 1 and 2 the top flange 10 beneath which the attaching members 6 of the buffer may be removably but rigidly secured as by the bolts 15, see Figs. 2 and 4. The rear end 11 of this extension supporting member may be similarly flanged over and bolted or otherwise secured to the frame 7 of the Ford or other automobile, suitable U-bolts or other connections 16 being, if desired, arranged to hold the central part of this supporting member to the front of the automobile frame adjacent the bracket 9 of the lamp 8. These connections 105 may comprise a U-bolt 12 extending around the bottom of the lamp bracket and tightened in connection therewith as by the nuts 16. The spring steel strips of which the buffer proper are composed may as indicated have considerably greater vertical width 110 than thickness so as to make them relatively

60

100

105

110

rigid vertically as compared to their resilient yielding action in horizontal directions, and in some cases may advantageously have arched or bent cross-sections to give increased stiffness and strength against horizontal bending strains, and if desired the entire strips may be first rolled or otherwise formed with such an arched or convex section as is shown in Fig. 2 and then bent into 10 or otherwise formed up to have the curved shape shown in plan in Fig. 1. In this way the arched or convex face 25 of these spring strips which are preferably tempered after having been bent into final shape projects 15 forward in the front members of the buffer and backward in the rear portions 5, the whole buffer being correspondingly strengthened and stiffened in its horizontal yielding action by this form of strip. An arched 20 cross-section strip has the added advantage that the doubled reinforced portions of the buffer fit and hold together more tightly and securely when the strips have this arched form, so that there is still less likelihood 25 of any slipping or working loose under operating conditions.

Another form of buffer of this same general character is shown in Figs. 3, 5 and 6 as comprising generally similar front members 1, 2, held together in reinforcing position by the clips 17 as just described. The outer extending portions 3 of these spring strips which are of arched or convex cross-section with the arched or curved face forward gradually merge into flat sectioned strips at the end loops 4 of the buffer, the arched front faces gradually growing flatter at the point shown at 22 so that the resilience of these end loops where the bending 40 strains are most severe is correspondingly increased and the buffer rendered less likely to break at this point. The inwardly and rearwardly curved portions 5 of this buffer may be given a similarly arched cross-section 45 in which the arched or convex face 24 is preferably turned forward, as shown in Figs. 3 and 5. The connecting attaching members 6 of the buffer may be bolted or otherwise secured to any suitable part of 50 the automobile or to a supporting member 23 secured thereto which may, if desired, have a similarly concaved face to be engaged by the curved attaching member of the buffer.

Fig. 7 shows a generally similar form of resilient spring strip buffer made of one piece of spring steel, the front portion 26 being given a forwardly curved or arched face 24 to increase its stiffness against bending and if desired this arched cross-section 60 may gradually merge at the points 22 into a flat sectioned strip at the open end loops 4 so that these parts can bend more readily and safely. The inwardly and rearwardly curved portions 5 which terminate in the

rearwardly extending attaching members 27 of the buffer may be given a similarly arched cross-section, the convex or arched face 24 of this strip being preferably forwardly arranged so that the buffer has a 70 more finished and artistic appearance. It is, of course, understood that the arched form of these spring strips shown in Figs. 3 and 7 may be formed by suitable bending machines in which the desired parts of the 75 strip are given this bent or arched cross-section.

Fig. 8 shows another form of resilient spring strip buffer in which the front or impact receiving member is given a forwardly bowed or arched outline preferably of uniform curvature. The end portions 29, 30 of the spring strips may overlap to form a reinforced impact receiving portion and the ends 40, 41 of the strips may, if desired, extend somewhat past the rearwardly extending attaching members 28 of the buffer for greater strength. These central impact receiving portions and also the outward extensions 3 thereof may be given an arched or bent cross-section preferably with the arched convex face forward and this may gradually merge at the points 22 into a flat sectioned strip of which the open end loops 4 are bent for greater resilience. The 95 inwardly and rearwardly extending portions 5 may be formed of strips having a similarly arched or bent cross-section with the arched convex face 24 arranged in front as indicated and this stiffened bent cross-section may cease adjacent the ends 28 of these strips so that the attaching ends 28 which may in some cases be bent upward more or less as indicated in Fig. 9, may be flat to be more readily attached to the frame 100 of an automobile by attaching bolts and operating slots or holes in the attaching members, as is well known in this art. As indicated in Figs. 9 and 10, the connecting or clamping means may comprise clips 28 110 forged or cast of malleable material and so curved at their inner faces as to accommodate the arched or curved cross-section strips which they hold together. The ends 32 of these clips may, of course, be angularly arranged so as to extend rearward and downward and be tightened by the bolt 31 so as to clamp the two spring strips together both horizontally and vertically. If the two 115 spring strips 29, 30 have the same arched cross-section their meeting faces will naturally come into contact adjacent the two edges of the strips since the forward convex faces of the strips naturally have a somewhat greater radius than the rear concave faces 125 thereof. It is also decidedly advantageous to have the upper and lower edges 40 of these spring strips beveled back in a rearward direction as indicated in Figs. 9 and 10, since this makes this edge less visible 130

or prominent as the buffer is ordinarily seen as compared to having it horizontally arranged. If desired also the rear edges of the spring buffer strips may be more or less 5 curved or rounded off as at 41 which increases this effect. With buffer strips of this general character in which the edges are backwardly relieved, cut away or beveled toward the rear, the front or other 10 curved faces of the strips may be nickel plated and polished or otherwise highly finished, which still further increases their relatively prominent appearance, while the edges of the strips may be enameled or 15 painted in dark colors or inconspicuously finished in other ways at relatively little expense as compared to grinding, nickel plating and polishing them. In some respects, furthermore, the buffer has a more 20 pleasing and artistic appearance when the front face is made relatively prominent and conspicuous as compared to the edges, and in this case it is still more desirable to have backwardly beveled or cut away edges to 25 minimize abrasion or removal of the finish thereon.

Fig. 11 shows another form of buffer in which the impact receiving members overlap so as to reinforce each other through- 30 out a relatively great extent of the buffer front and if desired this buffer may be formed with a forwardly bowed or arched outline of substantially uniform curvature as shown. The impact receiving members 35 33, 34, of this forwardly curved or bowed outline may with advantage be given an arched or bent cross-section to stiffen them against bending and render them correspondingly stronger where a light weight 40 spring strip of about a quarter or five-sixteenths of an inch thick and two to two and a quarter inches wide, more or less, is used as is desirable for the foregoing arched cross-section spring strip buffers for relatively light service. The forward strip or 45 member 34 may have one end 37 adjacent the connecting clip or connecting means 39, while its other end 47 may form the outer end of the buffer on the other side. The 50 rearward spring strip 33 may have one end 38 adjacent the opposite connecting clip 39 while its opposite end 48 may extend in front of the vehicle wheel on the other side. If desired, these connecting clips may not 55 only connect the two impact receiving members but also secure thereto the forwardly and outwardly curved ends 36 of the rearwardly attaching members, the general form of these clips being shown in Fig. 12. The 60 rearwardly extending attaching members may have flat sectioned ends 35 while the forwardly and outwardly curving portions 5 of these strips may be given an arched or bent cross-section with a convex front side 65 as indicated. This arched or bent cross-

section of the spring strips greatly facilitates the security and rigidity of their attachment and connection to each other, since tipping or relative bending of the strips is correspondingly minimized. As shown in 70 Fig. 12 the upper edges 42 of the spring strips and also the lower edges, if desired, may be backwardly beveled or cut away at a decided angle so as to make these edges practically invisible when the buffer is 75 looked at from the front and for similar reasons this form of strip makes more prominent the curved or arched front side of the strip which may be nickel-plated or otherwise highly finished and polished while 80 the strip edges may be enameled or painted in black or relatively inconspicuous colors.

This invention has been described in connection with a number of illustrative embodiments, forms, proportions, parts, arrangements, materials, methods of connection and use, to the details of which disclosure the invention is not of course to be limited, since what is claimed as new and what is desired to be secured by Letters 90 Patent is set forth in the appended claims:

1. The automobile buffer comprising two integral spring steel strips having greater vertical width than thickness to render them relatively rigid vertically while more resiliently yielding in horizontal directions, each of said strips having an attaching member to be attached to the automobile and having a transversely extending impact receiving member of forwardly bowed 100 outline having substantially uniform curvature and an intermediate open end loop to be arranged in front of the vehicle wheel and connecting means adjustably connecting said impact receiving members and holding them against relative vertical movement and forming overlapping members to stiffen and strengthen this part of the buffer, said impact receiving members and the intermediate portions of said attaching 110 members having a forwardly arched cross-section to stiffen the same against horizontal yielding and minimize relative vertical movement between said impact receiving members, said end loops being of substan- 115 tially flat cross-section to facilitate bending thereof.

2. The automobile buffer comprising two integral spring steel strips having greater vertical width than thickness to render them 120 relatively rigid vertically while more resiliently yielding in horizontal directions, each of said strips having an attaching member to be attached to the automobile and having a transversely extending impact receiving member of forwardly bowed outline and an intermediate open end loop to be arranged in front of the vehicle wheel and connecting means adjustably connecting said impact receiving members and holding them against 125

130

4. relative vertical movement and forming overlapping members to stiffen and strengthen this part of the buffer, said impact receiving members and the intermediate portions of said attaching members having a forwardly arched cross-section to stiffen the same against horizontal yielding and minimize relative vertical movement between said impact receiving members.
5. 3. The automobile buffer comprising two integral spring steel strips having greater vertical width than thickness to render them relatively rigid vertically while more resiliently yielding in horizontal directions, each of said strips having an attaching member to be attached to the automobile and having a transversely extending impact receiving member and an intermediate open end loop to be arranged in front of the vehicle wheel and connecting means adjustably connecting said impact receiving members and holding them against relative vertical movement and forming overlapping members to stiffen and strengthen this part of the buffer, said impact receiving members having a forwardly arched cross-section to stiffen the same against horizontal yielding and minimize relative vertical movement between said impact receiving members.
6. 4. The automobile buffer comprising two integral spring steel strips having greater vertical width than thickness to render them relatively rigid vertically while more resiliently yielding in horizontal directions, each of said strips having an attaching member to be attached to the automobile and having a transversely extending impact receiving member and an intermediate open end loop to be arranged in front of the vehicle wheel and connecting means adjustably connecting said impact receiving members and holding them against relative vertical movement and forming overlapping members to stiffen and strengthen this part of the buffer, said impact receiving members having a forwardly arched cross-section to stiffen the same against horizontal yielding and minimize relative vertical movement between said impact receiving members.
7. 5. The automobile buffer comprising two integral spring steel strips having greater vertical width than thickness to render them relatively rigid vertically while more resiliently yielding in horizontal directions, each of said strips having an attaching member to be attached to the automobile and having a transversely extending impact receiving member and an intermediate open end loop to be arranged in front of the vehicle wheel and connecting means adjustably connecting said impact receiving members and holding them against relative vertical movement and forming overlapping members to stiffen and strengthen this part of the buffer, said impact receiving members having a forwardly arched cross-section to stiffen the same against horizontal yielding and minimize relative vertical movement between said impact receiving members.
8. 6. The automobile buffer comprising two integral spring steel strips having greater vertical width than thickness to render them relatively rigid vertically while more resiliently yielding in horizontal directions, each of said strips having an attaching member to be attached to the automobile and having a transversely extending impact receiving member and an intermediate open end loop to be arranged in front of the vehicle wheel and connecting means adjustably connecting said impact receiving members and holding them against relative vertical movement and forming overlapping members to stiffen and strengthen this part of the buffer, said impact receiving members having a forwardly arched cross-section to stiffen the same against horizontal yielding and minimize relative vertical movement between said impact receiving members.
9. 7. The automobile buffer comprising a number of spring steel strips having greater vertical width than thickness to render them relatively rigid vertically while more resiliently yielding in horizontal directions, each of said strips comprising attaching members to be connected to the automobile and transversely extending impact receiving members of forwardly bowed outline having substantially uniform curvature and connecting clips encircling said impact receiving members and holding them against relative vertical movement and forming overlapping members to stiffen and strengthen the central front part of the buffer, said spring steel strips being formed throughout their impact receiving members and engaging portions with a forwardly arched cross-section to stiffen them against horizontal yielding and minimize relative vertical movement thereof, such portions of said strips having backwardly beveled upper edges and relatively prominent highly polished forward faces.
10. 8. The automobile buffer comprising a number of spring steel strips having greater vertical width than thickness to render them relatively rigid vertically while more resiliently yielding in horizontal directions, each of said strips comprising attaching members to be connected to the automobile and transversely extending impact receiving members of forwardly bowed outline and connecting means engaging said impact receiving members and holding them against relative vertical movement and forming overlapping members to stiffen and strengthen the central front part of the buffer, said spring steel strips being formed throughout their impact receiving members and engaging portions with a forwardly arched cross-section to stiffen them against horizontal yielding and minimize relative vertical movement thereof, such portions of said strips having backwardly beveled upper edges and relatively prominent highly polished forward faces.

tral front part of the buffer, said spring steel strips being formed throughout their impact receiving members and engaging portions with a forwardly arched cross-section to stiffen them against horizontal yielding and minimize relative vertical movement thereof, such portions of said strips having backwardly beveled upper edges and relatively prominent forward faces.

10. The automobile buffer comprising a number of spring steel strips having greater vertical width than thickness to render them relatively rigid vertically while more resiliently yielding in horizontal directions, said strips comprising attaching members to be connected to the automobile and transversely extending impact receiving members and connecting means engaging said impact receiving members and adjustably holding them against relative vertical movement and forming overlapping members to stiffen and strengthen the central front part of the buffer, said spring steel strips being formed throughout their impact receiving members 25 with a forwardly arched cross-section to stiffen them against horizontal yielding and minimize relative vertical movement thereof and such portions of said strips having backwardly beveled upper edges and relatively prominent forward faces.

10. The automobile buffer comprising a number of spring steel strips having greater vertical width than thickness to render them relatively rigid vertically while more resiliently yielding in horizontal directions, said strips comprising attaching members to be connected to the automobile and transversely extending impact receiving members and connecting means engaging said impact receiving members and adjustably holding them against relative vertical movement and forming overlapping members to stiffen and strengthen the central front part of the buffer, said spring steel strips being formed 45 throughout their impact receiving members with backwardly beveled upper edges and relatively prominent appearing forward faces.

11. The automobile buffer formed of spring steel strip having greater vertical width than thickness to render the same relatively rigid vertically while more resiliently yielding in horizontal directions, said buffer comprising attaching members to be attached to the automobile and a transversely extending impact receiving member and intermediate open end loops having flat section to facilitate bending to be located adjacent the automobile wheels, said spring steel 60 strip forming said impact receiving member having a forwardly arched cross-section to stiffen the same against horizontal yielding and having a backwardly beveled upper edge and a relatively prominent appearing 65 forward face.

12. The automobile buffer formed of spring steel strip having greater vertical width than thickness to render the same relatively rigid vertically while more resiliently yielding in horizontal directions, said 70 buffer comprising attaching members to be attached to the automobile and a transversely extending impact receiving member and intermediate end loops having flat section to facilitate bending to be located adjacent the automobile wheels, said spring steel strip forming said impact receiving member having a forwardly arched cross-section to stiffen the same against horizontal yielding.

13. The automobile buffer formed of spring steel strip having greater vertical width than thickness to render the same relatively rigid vertically while more resiliently yielding in horizontal directions, said 85 buffer comprising attaching members to be attached to the automobile and a transversely extending impact receiving member and intermediate end loops to be located adjacent the automobile wheels, said spring 90 steel strip forming said impact receiving member having a bent cross-section to stiffen the same against horizontal yielding.

14. The automobile buffer comprising two integral spring steel strips having greater vertical width than thickness to render them relatively rigid vertically while more resiliently yielding in horizontal directions, each of said strips having an attaching member to be attached to the automobile 100 and having a transversely extending impact receiving member and an intermediate open end loop to be arranged in front of the vehicle wheel and connecting means adjustably connecting said impact receiving 105 members and holding them against relative vertical movement and forming overlapping members to stiffen and strengthen this part of the buffer, the upper edges of said impact receiving members and of the intermediate portions of said attaching members being backwardly beveled and covered with an inconspicuously colored protective coating to minimize their prominence and the forward faces of said impact receiving 110 members being forwardly arched and nickel plated and polished to make their appearance relatively prominent.

15. The automobile buffer comprising two integral spring steel strips having greater vertical width than thickness to render them relatively rigid vertically while more resiliently yielding in horizontal directions, each of said strips having an attaching member to be attached to the automobile and having a transversely extending impact receiving member and an intermediate open end loop to be arranged in front of the vehicle wheel and connecting means adjustably connecting said impact receiving 115 mem- 120
125
130

- bers and holding them against relative vertical movement and forming overlapping members to stiffen and strengthen this part of the buffer, the upper edges of said impact receiving members being backwardly relieved to minimize their prominence and the forward faces of said impact receiving members being more strikingly finished to make their appearance relatively prominent.
- 10 16. The automobile buffer formed of spring steel strip having greater vertical width than thickness to render the same relatively rigid vertically while more resiliently yielding in horizontal directions, 15 said buffer comprising attaching members to be connected to the automobile and a transversely extending impact receiving member of forwardly bowed outline, said spring steel strip forming the forward impact receiving member having a forwardly arched cross-section to stiffen the same against horizontal yielding, having its upper and lower edges backwardly relieved and having a relatively prominent appearing highly polished forward face.
- 20 17. The automobile buffer formed of spring steel strip having greater vertical width than thickness to render the same relatively rigid vertically while more resiliently yielding in horizontal directions, 25 said buffer comprising attaching members to be connected to the automobile and a transversely extending impact receiving member, said spring steel strip forming the forward impact receiving member, 30
- 35
- a forwardly bent cross-section to stiffen the same against horizontal yielding, having its upper edges backwardly relieved and having a relatively prominent appearing highly polished forward face.
18. The automobile buffer formed of spring steel strip having greater vertical width than thickness to render the same relatively rigid vertically while more resiliently yielding in horizontal directions, 40 said buffer comprising attaching members to be connected to the automobile and a transversely extending impact receiving member, said spring steel strip forming the forward impact receiving member having 45 its upper edges backwardly relieved and having a relatively prominent appearing forward face.
19. The automobile buffer formed of spring steel strip having greater vertical width than thickness to render the same relatively rigid vertically while more resiliently yielding in horizontal directions, 50 said buffer comprising attaching members to be connected to the automobile and a transversely extending impact receiving member, said spring steel strip forming the forward impact receiving member having 55 its upper edges backwardly relieved and having a relatively prominent appearing forward face.
